US0D1045921S

(12) **United States Design Patent** (10) **Patent No.:** **US D1,045,921 S**
Gangishetty et al. (45) **Date of Patent:** **** Oct. 8, 2024**

(54) **DISPLAY SCREEN OR PORTION THEREOF
WITH GRAPHICAL USER INTERFACE**

(71) Applicant: **Caterpillar Inc.**, Peoria, IL (US)

(72) Inventors: **Ramya Gangishetty**, Dunlap, IL (US); **Keith R. Folken**, West Peoria, IL (US); **Russell Loring Stott**, Chapin, SC (US); **Patrick Cozad**, Canton, IL (US); **Varun K. Yellichetty**, Houston, TX (US); **Rajendra Behara**, Bangalore (IN); **Cybil E. Dsouza**, Peoria, IL (US); **Ryan C. Byrd**, Griffin, GA (US); **Edward M. Schroeder**, Germantown Hills, IL (US); **Theresa Annabring**, Mannheim (DE)

(73) Assignee: **Caterpillar Inc.**, Peoria, IL (US)

(**) Term: **15 Years**

(21) Appl. No.: **29/888,486**

(22) Filed: **Mar. 31, 2023**

(51) **LOC (14) Cl.** **14-04**

(52) **U.S. Cl.**

USPC **D14/486**

(58) **Field of Classification Search**

USPC **D14/485-495**

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of a display screen or portion thereof with graphical user interface showing our new design.

The peripheral dashed broken lines depict a display screen or portion thereof, and form no part of the claimed design.
